UNITED STATES PATENT OFFICE.

ROBERT J. DAVIS, OF DETROIT, MICHIGAN.

WEATHER-STRIP.

SPECIFICATION forming part of Letters Patent No. 650,637, dated May 29, 1900.

Application filed February 2, 1900. Serial No. 3,669. (No model.)

To all whom it may concern:

Be it known that I, ROBERT J. DAVIS, a citizen of the United States, residing at Detroit, in the county of Wayne, State of Michigan, have invented a certain new and useful Improvement in Weather-Strips; and I declare the following to be a full, clear, and exact description of the invention, such as will enable others skilled in the art to which it pertains to make and use the same, reference being had to the accompanying drawings, which form a part of this specification.

This invention relates to weather-strips for windows, and has for its object an improved strip of metal adapted to be secured to the framework of a window and to engage with the sashes of the window in a way to prevent the rattling of the sashes in their seats or the passage of air around the sashes. At the same time the sashes are left free to be raised or lowered and can be made in the first instance to so fit in their seats that the swelling of the sash-timber incident to damp weather will not cause the sash to bind in its seat.

In the drawings, Figure 1 is a horizontal cross-section of a side bar of the upper and a side bar of the lower sash of a window and of the frame in which the sash is seated. Fig. 2 is a cross-section of the upper cross-rail of the lower sash and the lower cross-rail of the upper sash. Fig. 3 is a perspective of an end of the weather-strip used with the outside sash. Fig. 4 is a perspective of an end of the weather-strip used with the inside sash. Fig. 5 is a perspective of an end of the weather-strip used on the meeting-rails of the sashes.

In Fig. 1, A indicates the side frame of the window. B indicates the parting-strip that extends upright between the two tracks or grooves that the sashes run in. C indicates the sash-stop at the inside of the frame. D indicates the blind-stop. a indicates a side rail of the lower sash, and b indicates a side rail of the upper sash.

The blind-stop extends inward from the frame-piece A. The parting-strip B is set in a groove in the frame-piece A and projects from the frame-piece extending into the opening of the frame. The sash-stop C is set on the frame A, and there is thus formed between the blind-stop D and the parting-strip

B a vertical groove extending from top to the bottom of the frame, and this groove constitutes the way or track that the upper sash travels in, and there is also formed between 55 the parting-strip B and the sash-stop C a similar vertical groove which constitutes the way or track for the lower sash. Each side strip of the sash is provided with a shallow vertical groove that is cut into the side strip 60 at a distance from the edge such that the groove registers with the face of the strip next adjacent to it on the outside. Thus the side rail b is provided with a groove c, that registers with the face of the blind-stop D. 65

The weather-strip e is made of sheet metal, one edge of which is provided with a flange e', extending its entire length, arranged to engage in a groove d, that is cut vertically in the blind-stop. The opposite edge of the 70 weather-strip e is turned back on itself, forming a smooth edge e² and also stiffening this part of the strip. Between the edge flange e' and the returned or doubled-back edge e² the web of the strip is bent with a single corrugation, forming a grooved part e³, which furnishes a track or rail for a screen f. The flange e' both stiffens the strip and furnishes an edge engagement in the groove d that is perfectly tight against the passage of air-drafts. The 80 edge e² engages in the groove c of the sash and effectually prevents the sash from rattling and also prevents the passage of air-currents around the sash. 75

The weather-strip for the lower sash is like 85 the weather-strip e, except that the vertical grooved part or corrugated part is omitted, and the web between the flange f' and the re-curved edge f² is straight and flat. The re-curved edge f² engages in a groove g cut vertically in the side rail a of the sash, and the flange f' engages in a vertical groove in the parting-strip B. Both weather-strips are secured in the woodwork by nails. 90

On the lower side of the meeting-rail of the 95 outer sash is secured a weather-strip h, provided with a flange h', that is set into a groove k in the meeting-rail K. This weather-strip h is arranged to project inward beyond the edge of the meeting-rail K, and the projecting part is grooved or corrugated with a corrugation h², that stiffens this part of the 100

weather-strip and engages closely against the lower side of the meeting-rail of the lower sash.

What I claim is—

- 5 1. The combination of the blind-stop D, having a groove d , therein, a window-frame provided with a groove e , a weather-strip e , provided with a flange e' , said flange being adapted to lie flat upon said blind-stop and 10 being bent at right angles to extend into the groove d , said weather-strip being bent upward and then downward to form a grooved part e^3 , and extending in a flange e^2 , along the surface of said blind-stop and into the 15 groove in the window-frame, and a screen f , adapted to slide upon the grooved part, e^3 , of the weather-strip, substantially as described.
- 20 2. The combination of a blind-stop D, a window-frame provided with a groove e , a weather-strip e , provided with a flange e' , said flange being adapted to lie flat upon said blind-stop, said weather-strip being bent upward and then downward to form a grooved 25 part e^3 , and extending in a flange e^2 , along the surface of the blind-stop, and into the groove in the window-frame, and a screen f , adapted to slide upon the grooved part e^3 ,

of the weather-strip, substantially as described.

3. The combination of a window-stop provided with a groove, extending longitudinally thereof, a window-sash provided with a longitudinal groove g , the inner bounding surface of which is approximately on a line 35 with the outer surface of said stop, and a weather-strip provided at one edge with a flange f' , of greater height than the depth of the groove in the window-stop, said weather-strip having its flange f' , extending into the 40 groove in the window-strip and its opposite edge extending into the groove in the window-sash so as to hold its intermediate web out of contact with the stop, and an adjustable means for connecting said web to the 45 window-stop, whereby the tension of the strip upon the bounding surface of the groove g , may be adjusted, substantially as shown and described.

In testimony whereof I sign this specification in the presence of two witnesses.

ROBERT J. DAVIS.
